UNITED STATES PATENT OFFICE.

THOMAS L. SHIELDS, OF SEATTLE, WASHINGTON.

FARE-BOX CLAMP.

Application filed October 20, 1926. Serial No. 142,844.

The invention is a clamp for readily attaching a change dispenser to a fare box, such as is ordinarily used on street railway systems.

5 The object of the invention is to provide a simple and efficient means for holding a change dispenser to a fare box.

Another object of the invention is to provide a clamp that may readily be attached 10 to, or made integral with a change dispenser and which will readily hold the change dispenser to a fare box.

A further object of the invention is to provide a clamp on a change dispenser which 15 will readily operate to grip the members of a fare box and hold the dispenser in place as it is placed thereon.

And a still further object of the invention is to provide a change dispenser clamp by 20 which the dispenser may readily be held to or removed from a fare box.

With these ends in view the invention embodies a clamp comprising two parallel bars, that may be placed at the rear of a change 25 dispenser; movable jaws pivotally attached to the said bars and a vertically disposed hook for operating the said jaws and holding the device to the top of the fare box.

Other features and advantages of the invention will be seen from the following description, taken in connection with the drawings, wherein:

Figure 1 is a view showing the device as it would appear while holding the change dispenser in place.

Figure 2 is a rear view showing the rear of the clamp.

Figure 3 is a vertical section through the clamp.

40 Figure 4 is a plan view with the vertical hook broken away.

Figure 5 is a plan view showing the lower bar.

In the drawings the device is shown as it 45 would be made, wherein numeral 1 indicates a horizontal bar which has extensions 2 at the ends that are held to the ends of the change dispenser by bolts 3 as shown in Figure 4. At the center of the bar 1 is a downwardly extending vertical member 4 that connects the bar to another horizontal bar 5 and the bar 5 is provided with projections 6 adjacent its ends which will engage the inner sides of posts which are indicated by the numeral 7, 50 of the fare box. Clamps 8 are pivotally attached to the bar 5 at the points 9 and 10

and are held to the bar 1 by pins 11 which are attached to the bar 1 and which project through slots 12. These clamps are freely mounted and are readily moved inward or 60 outward by the vertical bar 13 through slots 14 in the horizontal projections 15 in which pins 16 of the clamps 8 extend. The bar 13 is provided with a hook 17 at the upper end and is slidably held upon pins 18 and 19 which extend through slots 20 and 21. It will be observed that as the hook 17 is pushed downward the projections 15 will move downward and the clamps 8 will move outward, and when the hook is moved upward 70 the slots 14 will draw the pins 16 and the clamps 8 inward so that the hooks 22 at the ends of the clamps 8 will grip and hold the device to the rods 7, as shown in Figure 1.

It will be understood that changes may be 75 made in the construction without departing from the spirit of the invention, one of which changes may be in the exact design or shape of either of the members, another may be in the use of other means for attaching the 80 clamp to the change dispenser and still another may be in the use of other means for operating the clamp members.

The construction will be readily understood from the foregoing description. To use the 85 device it may be made as shown and attached to the plate at the ends of a change dispenser by the bolts 3 and it will be observed that as it is placed upon the fare box the rods 7 of the fare box will pass between the projections 90 6 and the hooks 22 and when the dispenser is moved downward with the hook 17 on the upper edge of the fare box the hooks 22 will be drawn inward to grip the device around the rods 7. It will also be observed that when 95 it is desired to remove the device the dispenser may be moved upward and as the hook 17 is pushed downward it will move the hooks 22 outward and release the dispenser from the fare box. This device may readily be attached to a change dispenser having any suitable number of coin tubes as the bar 1 may be made longer or shorter as may be desired.

Having thus fully described my invention what I claim as new and desire to secure 105 by Letters Patent is:

1. In a device of the class described, two parallel bars with a connection between them, means for rigidly attaching the ends of one of the bars to an object, clamp members with 110 hooks at their outer ends pivotally attached to one of the said bars and slidably held to the

other of the said bars, the hook ends of the said clamp members being adapted to be moved longitudinally of the said bars, a vertical member with a hook at the upper end 5 slidably attached to the said bars and means connecting the said vertical member to the said clamp members whereby the hooks on the said clamp members will move outward or inward as the vertical member moves upward 10 or downward.

2. In a clamp for change boxes or the like, a horizontal bar adaptable to be attached to the upper end of the said change box, another horizontal bar attached to the former bar by 15 a vertical member and adaptable to bear against the rear of the said change box, said latter bar having projections extending outward a short distance from each end, clamp members with hooks at their outer ends pivotally attached to the latter of the said horizontal bars and slidably held to the former bar, a vertical bar with a hook at the upper 20 end and projections at the side slidably held to the vertical member between the two bars,

said projections of the said vertical member 25 having inclined slots at their outer end and pins on the said clamp members extending through the said slot, said members being arranged to move the hooks at the ends of the clamps outward as the vertical rod is moved upward and inward as the said rod is moved downward.

3. In a clamp of the class described, a pair of laterally movable hooks at the ends of angular shaped members, a frame having two 30 horizontal members connected by a vertical member at the center upon which the said angular shaped members are pivotally and slidably mounted, a vertical member having horizontal projections also slidably mounted 35 upon the said frame and means for connecting the horizontal projections of the vertical member to the angular shaped members to cause the hooks to move outward or inward as the vertical member is moved upward or 40 downward.

In testimony whereof I affix my signature.
THOMAS L. SHIELDS.
